WAVE SIGNALING SYSTEM

Harold A. Wheeler, Great Neck, N. Y., assignor to
Hazelton Corporation, Jersey City, N. J., a corporation of Delaware

Application May 31, 1934, Serial No. 728,440

8 Claims. (Cl. 250—20)

This invention relates primarily to improvements in tuned radio broadcast receivers adapted to reproduce speech or music.

An object of the invention is to provide an economical but effective means of securing a high degree of fidelity in signal reproduction free of interference from stations operating on carrier channels adjacent that of the station being received.

10 A factor which militates against perfect reproduction of speech or music in radio broadcast reception resides in the allocation of broadcasting channels at frequency intervals of only 10 kilocycles, whereas the important frequencies present in speech and music cover a range on the order of this figure. Receiving a band sufficiently wide to include sidebands corresponding to the entire range of acoustical frequencies would, therefore, result in interference from the carriers of the adjacent broadcasting channels.

A high degree of fidelity in signal reproduction is obtainable by receiving audio frequencies within an upper limit of less than 10 kilocycles. Therefore, to achieve the optimum in fidelity consistent with avoidance of interference, the selectivity characteristic of a receiver should be of rectangular shape and such as to provide uniform response throughout a frequency band of slightly less than 10 kilocycles for single side band and slightly less than 20 kilocycles for double side band reception, with complete suppression or infinite attenuation of frequencies outside this band.

It is a relatively difficult and expensive matter to approximate the ideal rectangular selectivity characteristic in tuned radio or intermediate frequency coupling systems such as are employed in commercial radio broadcast receivers. In general the cutoff provided by such coupling systems is sufficiently gradual that substantial elimination of interference from broadcasting channels adjacent that being received, is secured only at an appreciable sacrifice in fidelity of signal reproduction due to non-uniform reception of the carrier sidebands.

In accordance with the present invention, fidelity in signal reproduction free from interference is achieved by utilization in the radio and intermediate frequency portions of a receiver, of tuned couplings having sufficiently broad band response to receive nearly uniformly carrier sidebands sufficiently wide to include the important range of frequencies occurring in speech and music. Interference from adjacent broadcasting channels is then eliminated by interposition in

the audio frequency circuits of the receiver of one or more wave traps tuned to the frequency difference between adjacent carrier channels.

In the drawing:

Fig. 1 is a circuit diagram of a superheterodyne receiver containing the invention.

Fig. 2 illustrates graphically the relative overall response from the antenna circuit to the loud speaker output of a receiver, such as that of Fig. 1.

Figs. 3 to 5 inclusive, show modified forms of "wave traps" applicable to the loud speaker circuit of the Fig. 1 system.

In the system of Fig. 1, an antenna circuit A is coupled through a tunable selector T₁, comprising a transformer having a condenser tuned secondary, to the input of a stage of radio-frequency amplification, tube V₁. The output of tube V₁ is in turn coupled through a tunable selector T₂, similar to T₁, to the input of a modulator tube V₂.

Heterodyne oscillations are applied to the modulator input by means of a resistance R₂ through which the cathodes of the modulator tube V₂ and an oscillation generator, tube V₃, are grounded in common. Tube V₃ is adapted to generate oscillations of heterodyne frequency by reason of a tuned impedance T₃, grounded at an intermediate point G₃, and connected from the grid of tube V₃ through a blocking condenser b to its anode.

The modulated output of tube V₂ is selectively applied to a stage of intermediate frequency amplification, tube V₄, through a selector T₄, consisting of a transformer, the primary and secondary coils of which are permanently tuned by the shunt condensers to the modulated or intermediate frequency. A rectifier, tube V₅, receives the output of tube V₄ through a permanently tuned selector T₅, similar to T₄.

The rectified output is applied through a variable tap potentiometer R₅, or volume control, to a stage of audio-frequency amplification, tube V₆, and thence through a stage of push-pull amplification, comprising tubes V₇ and V₈ interposed between audio-transformers T₇ and T₈, to an electro-acoustical device or loud speaker S, actuated by a voice coil L₂.

The tunable selectors T₁ and T₂ and the permanently tuned selectors T₄ and T₅, are broadly tuned to respond nearly uniformly over a frequency band approximately 14 kilocycles wide. The resulting overall selectivity is, however, insufficient against interference from the broadcasting channels spaced, according to existing practice, at 10 kilocycle intervals from the station selected. This condition is corrected, in accordance with the present invention, by one or

more "wave traps" W , W_1 , W_2 , interposed in audio-frequency circuits of the system. Each of these traps is tuned to 10 kilocycles for suppressing the audible carrier beat notes due to adjacent broadcasting channels.

The audio-frequency amplifier tube V_6 is a pentode. This type of tube is particularly well adapted to the use of traps, such as W_1 and W_2 in its cathode and anode circuits respectively, because with a pentode or screen grid type of tube, the cathode and anode circuits are nearly independent of each other, and the trap action is therefore simple.

In the anti-resonant 10 kilocycle trap W_1 , interposed in the common input and output path electrically linking the cathode, control grid, and anode of the tube V_6 , the values of coil L_1' and the shunt condenser C_1 are such that their reactances at 10 kilocycles are of the same order of magnitude as the mutual resistance (reciprocal of mutual conductance) of tube V_6 . The trap action is nearly independent of other properties of the tube and associated circuits and functions to suppress a selected high audio-frequency comprised in, or constituting a component of, the audio-frequency current traversing the common path between the input and output circuits of the tube V_6 .

The 10 kilocycle trap W_2 includes a condenser C_2 in series with an inductance L_2' across the plate-circuit of tube V_6 , namely, across the primary P_7 of the audio-frequency transformer T_7 . The usual high audio-frequency peak of the transformer is damped out by a high resistor R_7 across the secondary S_7 . Each of the two impedances C_2 and L_2' , is, at 10 kilocycles, of the same order of magnitude as the apparent impedance of the transformer primary P_7 , the latter impedance being determined largely by the resistor R_7 connected across the secondary S_7 and thus effectively shunting the series connected coil L_2' and condenser C_2 . This relation, which is made possible by the exceedingly high plate-resistance of the pentode tube V_6 , has the advantage of being independent of tube characteristics.

The voice coil trap W , tuned to 10 kilocycles, comprises a coil L , bridged in series with a condenser C across the voice coil L_2 of the speaker S , and also across the secondary of the audio-transformer T_8 . L_1 denotes secondary leakage inductance of transformer T_8 , which is the apparent secondary inductance measured with the primary short circuited. The preferred relation between the inductances L_1 , L_2 and L as measured at a frequency near 10 kilocycles, is:

$$(1) \quad L_1 + L_2 = 2L$$

This gives a cut-off frequency of 7 kilocycles with the trap W tuned, as stated. If L_1 and L_2 are unequal, nearly as good results are obtained if:

$$(2) \quad L = \frac{L_1 L_2}{L_1 + L_2}$$

That is, L equals the inductance of L_1 and L_2 in parallel. None of these relations is critical except the tuning of trap W to 10 kilocycles.

Usually only one or two of these three traps W , W_1 and W_2 , shown in Fig. 1, is required. The cathode trap W_1 employs reactance values for elements L_1' and C_1 which are at 10 kilocycles, on the order of 1000 ohms, and are usually most easily and cheaply secured. The voice coil trap W gives the best performance, however, because

of its cooperation with the inherent inductance, such as L_1 and L_2 , of the circuit.

In Fig. 2, curves A and B show by way of comparison the effect of the voice coil trap W alone, that is, omitting the cathode and plate traps W_1 and W_2 respectively. These curves represent the overall behavior of the entire receiver, including both the carrier frequency and audio-frequency portions. The dotted curve A, graphically depicting the output with the voice coil trap W omitted, indicates insufficient selectivity against 10 kilocycle beat notes from adjacent carrier channels. Curve B, illustrative of the response with trap W included in the circuit, indicates the greatly improved selectivity against 10 kilocycle beat notes obtained without impairing the output over the most useful audio-frequency range of 50 to 7000 cycles; several octaves.

The relationships of Equations (1) and (2) are largely responsible for the sharp cut-off between 7 and 10 kilocycles represented by curve B.

Fig. 3 shows a modified form of voice coil trap which is preferred when L_1 is less than L_2 . The preferred relation of inductances is:

$$(3) \quad L_1 + L_3 = L_2 = 2L$$

If L_1 is greater than L_2 , the preferred modification is that of Fig. 4 when:

$$(4) \quad L_1 = L_2 + L_4 = 2L$$

The modification of Fig. 5 permits of the greatest flexibility in design, although it is usually unnecessary to refine the circuit to this extent. Assuming the inductances L , L_1 , and L_2 and the resistance R_2 of the speaker voice coil to be measured at 7 kilocycles, then the preferred relations are:

$$(5) \quad L_1 + L_2 = L_3 + L_4 = 2L$$

$$(6) \quad R_2 = \sqrt{L/2C}$$

None of the above relations is critical, except that L and C must, as stated, be accurately tuned to 10 kilocycles in all cases.

The voice coil trap W in all of its modifications improves the efficiency of the speaker S with increasing effectiveness as the cut-off frequency of 7000 cycles is approached. Below resonance, i.e., below 10 kilocycles, trap W is capacitively reactive and of a magnitude which increases rapidly with approach to resonance. On the other hand the reactance of the voice coil L_2 is inductive, and may be such at the higher audio-frequencies around 7000 cycles, as to reduce the power factor of the coil to around 50 percent. The capacitive reactance of the trap accordingly increases with frequency in such relation to the accompanying variation in inductive reactance of the voice coil as to maintain throughout the active audio-frequency range a relatively high efficiency of signal energy transfer.

I claim:

1. In a tuned radio broadcast receiving, rectifying and signal reproducing system, means re-laying the rectified signals including a vacuum tube having cathode, anode, control grid and screen grid electrodes, a common input and output path electrically linking said cathode and said control grid and anode, and means for suppressing a selected high audible frequency comprised in said path and including a coil and condenser in parallel the component reactances of which are, at said selected frequency, of the same order of magnitude as the mutual resistance of said tube.

2. In a tuned radio broadcast receiving, rectifying and reproducing system, means relaying the rectified signals including a screen grid vacuum tube having an anode and a cathode, and means for separately selecting and suppressing audible carrier beat notes comprising a resistive impedance effectively shunting a coil and condenser connected in series between said cathode and anode, the component reactances of said coil and condenser being, at the beat note frequency, of the same order of magnitude as said resistive impedance.

3. In a tuned radio broadcast receiving, rectifying and reproducing system, an electro-acoustical responsive device having an actuating coil of inductance L_2 coupled to said system through a transformer having a secondary leakage inductance L_1 , a resonant path tuned to a high audible frequency to be suppressed shunting said actuating coil, said path including a condenser in series with a coil of inductance L , the several coils being relatively so proportioned that their inductances effective near said suppressed frequency satisfy substantially the relation:

$$25 \quad L_1 = L_2 = 2L.$$

4. In a tuned radio broadcast receiving, rectifying and reproducing system, an electro-acoustical responsive device having an actuating coil of inductance L_2 coupled to said system through a transformer having a secondary leakage inductance L_1 , a resonant path tuned to a high audible frequency to be suppressed shunting said actuating coil, said path including a condenser in series with a coil of inductance L , the several coils being relatively so proportioned that their inductances effective near said suppressed frequency satisfy substantially the relation:

$$40 \quad L = \frac{L_1 \cdot L_2}{L_1 + L_2}$$

5. In a tuned radio broadcast receiving, rectifying and reproducing system, an electro-acoustical responsive device having an actuating coil of inductance L_2 connected in series with a coil of inductance L_3 to said system through a transformer having a secondary leakage inductance L_1 , a resonant path tuned to a high audible frequency to be suppressed shunting said actuating coil, said path including a condenser in series with a coil of inductance L , the several coils being relatively so proportioned that their inductances ef-

fective near said suppressed frequency satisfy substantially the relation: $L_1 + L_2 = L_3 = 2L$.

6. In a tuned radio broadcast receiving, rectifying and reproducing system, an electro-acoustical responsive device having an actuating coil of inductance L_2 connected in series with a coil of inductance L_4 to a system through a transformer having a secondary leakage inductance L_1 , a resonant path tuned to a high audible frequency to be suppressed shunting the transformer secondary coil, said path including a condenser in series with a coil of inductance L , the several said coils being relatively so proportioned that their inductances effective near said suppressed frequency satisfy the relation: $10 \quad L_1 = L_2 + L_4 = 2L$.

7. In a tuned radio broadcast receiving, rectifying and reproducing system, an electro-acoustical responsive device having an actuating coil of inductance L_2 , connected in series with coils of inductances L_4 and L_3 respectively to said system through a transformer having a secondary leakage inductance L_1 , a resonant path tuned to a high audible frequency to be suppressed, bridged across said actuating coil and the coil of inductance L_4 , said path including a condenser of capacity C in series with a coil of inductance L , the several said coils being relatively so proportioned that their inductances effective near said suppressed frequency satisfy substantially the relation: $20 \quad L_1 + L_2 = L_3 + L_4 = 2L$.

8. In a tuned radio broadcast receiving, rectifying and reproducing system, an electro-acoustical responsive device having an actuating coil of inductance L_2 and of resistance R_2 , connected in series with coils of inductances L_4 and L_3 respectively, to said system through a transformer having a secondary leakage inductance L_1 , a resonant path tuned to a high audible frequency to be suppressed, bridged across said actuating coil and the coil of inductance L_4 , said path including a condenser of capacity C in series with a coil of inductance L , the several said coils and said condenser being relatively so proportioned that said inductances effective near said suppressed frequency satisfy substantially the relations: $25 \quad L_1 + L_2 = L_3 + L_4 = 2L$; and $30 \quad 40 \quad 45 \quad 50$

$$R_2 = \sqrt{\frac{L}{2C}}$$
